UNITED STATES PATENT OFFICE.

JOHN KING KAHL, OF ST. LOUIS, MISSOURI.

AUTOMATIC TOY.

1,390,136.

Specification of Letters Patent.

Patented Sept. 6, 1921.

Application filed November 10, 1919. Serial No. 336,842.

To all whom it may concern:

Be it known that I, JOHN KING KAHL, a citizen of the United States, residing at St. Louis, in the county of St. Louis, city and 5 State of Missouri, have invented a new and useful Automatic Toy, of which the following is a specification.

This invention relates to the class of games and toys, and more particularly to an im- 10 proved automatic or motor operated toy, which for purposes of convenience, I call an automatic anvil chorus toy.

It is the object of the invention to pro- 15 vide an improved actuating means for a toy of the above class, adapted to be operated by a spring motor capable of being wound as desired, whereby two objects will be caused to strike blows on an anvil and to give corresponding sounds for the amusement especially of children.

With the above and other objects in view, which will appear as the description pro- 20 ceeds, the invention resides in the combination and arrangement of parts and in the de- tails of construction hereinafter described 25 and claimed, it being understood that within the scope of what is claimed, changes in the precise embodiment of the invention shown can be made without departing from 30 the spirit of the invention.

In the accompanying drawings:

Figure 1 is a front elevation of my im- 35 proved automatic toy;

Fig. 2 is an end elevation;

Fig. 3 is a plan view;

Fig. 4 is a rear elevation thereof;

Fig. 5 is a transverse sectional view taken 40 on the line 5—5 of Fig. 4.

Referring to the drawing in detail, in 45 which like reference characters designate similar parts throughout several views, the numeral 10 designates a casing preferably provided with a bottom wall 11, a front wall 12 and end walls 13. The top and rear side 50 of the casing are open and said casing upon the bottom wall 10 is designed to support a spring motor 14 comprising a suitable frame 15 supporting the actuating mechanism de- signed to be operated by a spring 16 and a 55 suitable train of gearing 17 including a ratchet device or pallet mechanism 18 for regulating the speed of operation thereof. The winding shaft 19 extends through the front of the casing for the application of a 60 suitable key 20, by which the spring may be wound to permit operation of the device.

The end walls 3 are provided with recesses 21 adapted to receive a cross bar 22 carrying figures 23 and 24 pivoted adjacent the end walls 13. These figures are bifurcated at 60 the lower ends as shown at 25, the pivots thereof being designated at 26 so as to permit said figures to swing toward and away from the anvil 27 mounted upon the cross bar 22 intermediately of its length. 65

The lower bifurcated ends of the figures which might be of suitable configuration, are connected by a rod 28 having connection through a connecting rod 29 to one side of the longitudinal center thereof, eccentrically with a crank disk 30 suitably driven by the motor. Thus, when the motor is actuated, the connecting rod will impart reciprocating motion to the rod 29, thus causing oscillation of said figures toward and 70 away from the anvil. Each figure carries in the arms 31 thereof, a hammer or sledge 32 adapted to strike the anvil, and as each of the hammers and the anvil are made of different metals, a different sound or tone will 75 be produced for each stroke of the hammer as the same are caused to successively strike the anvil, to produce the anvil chorus or tune.

Having thus fully described the invention what I claim is:

In a device of the character described, a casing, said casing including side walls, pivot pins connecting the side walls adjacent to the ends thereof, a cross bar, end 90 walls forming a part of the casing and having connection with the cross bar, said pivot pins extending through the cross bar, figure members, said figure members having bifurcated portions adapted to embrace portions of the cross bar, said pivot pins passing through the bifurcated portions of the figure members, a rod connecting the lower extremities of the bifurcated portions adjacent to the lower ends thereof, a motor 100 positioned within the casing, a connecting rod operated by the motor and connected to the rod for imparting reciprocating motion thereto, for operating the figure members.

In testimony that I claim the foregoing 105 as my own, I have hereto affixed my signature in the presence of two witnesses.

JOHN KING KAHL.

Witnesses:

MABEL LEWIS,
W. T. KEIL.
